CONCENTRATED BEAM LIGHT

Application filed May 2, 1927. Serial No. 188,817.

This invention relates to improvements in concentrated light beam illumination, such as headlights for vehicles, searchlights or other uses.

One of the objects of this invention is to provide primary reflector means whereby rays reflected from points on the reflector farthest from the light source are projected at greater divergence from the principal axis than rays reflected from points on the said reflector nearer the light source, which is located substantially at an assumed focal point.

Another object of this invention is to provide means to offset and correct tolerance effects caused by imperfections and defects occurring in light bulbs, light sources, sockets, sleeves and reflected surfaces, which cause objectionable defects of light rays from the theoretical or normal course.

Another object of this invention is to provide a method of concentrated light beam illumination, which allows more complete and accurate control of all light rays, and which will permit a greater predetermined allocation of substantially all of the light by modifying and correcting divergences in the rays forming the light beam.

Another object of this invention is to provide a primary reflector having a particular form generated by an arbitrary decrement, which will permit the accurate placement of all the rays from the filament source to the final object without glare and whereby the rays most sensitive to deviations in the reflector surfaces and to errors and tolerances in the filament construction, will be so positioned that they can not come within the range of an observer in front of the vehicle, and whereby the rays reflected from the portions of the reflector less sensitive and less dependent to deviations of the reflector surfaces, tolerance in the filament, etc., are placed substantially nearer the top of the final beam when the light source is placed on the vehicle.

Another object of this invention, as compared with the usual parabolic reflector, is to so construct the reflector surfaces behind the parametric plane that the surfaces behind

the parametric plane are not substantially more sensitive to tolerances and defects, than surfaces on the parametric plane, and the rays from such portions of the reflector may be directed substantially parallel to the horizontal axis of the headlight. 55

Other and more detailed objects of this invention will appear from the following description thereof, taken in conjunction with the attached drawings, illustrating the preferred forms of embodiment of my device 60 and in which

Figures 1, 2, and 3 illustrate diagrammatically basic forms of the various curves used in my reflectors. 65

Figure 4 is a center section thru a completed reflector, showing in detail the construction of the five different portions of the complete reflector.

Figure 5 is an enlarged central section of the reflectors showing the paths of certain of the rays therefrom. 70

Figures 6 and 7 are similar to Figure 4, showing modified forms of primary and secondary reflectors. 75

Figures 8 and 9 are respectively the plan and cross sectional views of the secondary reflector, shown in Figure 4.

Figures 10 and 11 are respectively the plan and cross sectional view of the secondary reflector shown in Figure 6. 80

Figure 12 is a vertical cross section of my improved headlight.

Figure 13 is a diagrammatic showing of my dual headlight. 85

It is to be noted that my headlight may comprise three principal parts, the primary reflector which is formed by the revolution of a generated curve about a right line, a secondary reflector adjacent thereto which has an irregular surface specifically plotted and that part of the primary reflector below a perpendicular plane thru a reference point in the axis, which is the parametric plane, and which may have any one of several forms. 90

I have discovered when the curvature of a reflector surface is generated by taking as the factors some coefficient of the gradually decreasing angles formed by the side of the cones of rays, as the successive assumed 100

reflecting points recede from an assumed reference point, comparative with the focal point of a parabolic reflector, which coefficient may be a constant but which is preferably a variant coefficient, and where such factors are cumulative, that it is possible to get far better and very much more flexible control and allocation of the rays and light flux than is possible with a paraboloidal reflector or any regular modification of a paraboloid or any surface generated upon any regular factor or line comparative with the directrix of a parabola.

I have also discovered that the objectionable effects of tolerances in light bulbs and sockets and defects in reflecting surfaces as elements of objectionable glare in the usual parabolic form of headlight reflectors, due to the proximity of the reflecting surfaces between the parameter and the heel of the reflector to the light source, may be largely eliminated by making all or a portion of this part of the reflecting surfaces concentric upon the assumed reference point with a radius substantially equal to the radius at the parameter, or part concentric and part shaped in a manner similar to the portion between the parameter and the rim of the reflector, with the distance from the assumed reference point maintained substantially equal to that of the concentric portion. This manner of shaping this part of the reflector will also result in reducing the diameter of the light beam to about one half that of the usual parabolic reflector of comparative dimensions and thereby greatly increases the condensation of the light flux in an area approximately one fourth that of the paraboloid.

In Figures 1, 2 and 3, I have illustrated three forms of curves and the particular resulting cones of rays from each. Figure 1 may be arbitrarily termed the plus or increment curve which indicates that the change of curvature is brought about by the addition of successive increments to a variable angle, which is the tangent angle of a parabola, the increments being small and it may be a variable percentage of the angle between the sides of the cone of rays at the point considered. The effect of this addition of increments to form the plus or increment curve may best be illustrated by taking some point, such as the point 10 on the primary reflector and which is a known distance from the assumed reference point F. It will be noted that the cone of rays F-10-F' is formed because of the finite size of the filament. The reflection from the reflector point 10 is the cone of rays R-10-R'. If the tangent to the reflector surface at the point 10 was the same as the tangent to a paraboloidal reflector at a similar point, the center line of the ray would be parallel to the axis thru the focus. In view of the fact however, that a positive

percentage increment has been added to the tangent at such point of surface, the ray F-10 is reflected along the line 10-R at an angle to the axis.

The point 11 shows in more exaggerated form, the same condition in which the outer rays of the cone of rays from this point, rays R² and R³ are at a greater angle from the axis than the rays R and R'. This is because the increments are so cumulative as to increase the tangent of the reflector at the point a greater amount at the points farther out from the filament.

Comparing this curve with the curve of an ordinary parabola as shown in Figure 2, it is found that every point of my curve, beginning at the reference plane and moving progressively outwardly, is nearer to a line corresponding to the directrix than to a reference point corresponding to the common focus. The progressive decrement, being a cumulative factor successively of the angles formed between the two sides of the several respective cones of rays reflected from the sequential points assumed to form such curve, the curve formed will be continuous but not normally of any regular increment of curvature. Preferably it will be of irregular increment of curvature, variable at will to meet the assumed requirements, and the cones of rays reflected from such sequential points and points intermediate may be definitely controlled in a desired manner assumed for them so that the light flux may be condensed or diffused on any assumed areas to be illuminated. In this form of the curve, points on the reflector surface farthest from the assumed reference point will reflect cones of rays, so that rays in the middle of the cones of rays are projected at greater angles away from the principal axis than the middle of a cone of rays reflected from points nearer to the assumed reference point. Theoretically, in the parabolic section shown in Figure 2, the centers of the cones of rays are parallel to the central axis through the focus.

In Figure 3, I have illustrated a portion of a curve which may be arbitrarily termed the minus or decrement curve. The middle ray of the cone of rays at the point 13, which is nearer to the filament, not shown, is at an inclining angle to the line of the principal axis thru the reference point, which in the paraboloid would be termed the axis and this ray is not only at an angle to the axis but is at the opposite angle to the cone rays at the point 10 on the plus or increment curve. From the point 12 at a greater distance from the reference point, the middle ray of the cone of rays is at a greater angle to the so-called axis, which angle is opposite that of the cone of rays from the point 11, in view of the fact that cumulative decrement is taken from the tangent to the ray at that point.

The specific manner of generating these curves will be explained hereinafter, but the use of the terms plus or increment and minus or decrement is intended to mean and is used herein to indicate curves one of which would extend outside of a parabolic section and the other of which will extend inside a parabolic section of comparative dimensions.

The center section thru one form of a light reflector is shown in Figure 4. For the purpose of explaining the different sections, it may be considered to be divided into five sections, section 1 of which is that portion of the primary reflector above the parametric plane. 15 The side of this reflector is the same as the curve shown in Figure 1, and is merely a surface of revolution about a right line thru the reference point.

The second section is concentric about the reference point, the radius being not substantially less than and preferably equal to the distance from the reference point to the primary reflector curve on the parametric plane, which is shown as the distance F—Po. This 25 portion is limited by a line drawn from the lip of the reflector thru a point, which is the maximum position to which the filament may extend within the limits of guaranteed tolerance. With the usual construction, and with 30 present standards, this point will be $\frac{1}{32}$ of an inch above the predetermined reference point F. The intersection of the line from the lip thru this maximum position with the arc forming the lower extremity of this portion 35 is the location of the point C.

Section 3 is a substantially cylindrical section having but sufficient pitch in its side so that the reflector may be withdrawn from a suitable mold. The diameter at the top is 40 equal to the diameter at the point C and the diameter at the point D is only a fraction less, the angle being of the nature of a few degrees from a true cylinder.

Section 4 which adjoins section 3 is paraboloidal so that substantially all of the rays are projected parallel to the axis. It is to be noted however, that a substantial portion of this base is dead and does not reflect light, because of the presence of the light socket. 50 Section 4 is spaced from the filament by the use of the substantially cylindrical section 3, merely for the purpose of spacing the points thereon at a substantially as great distance from the filament F, as the point Po.

55 The section which is the secondary reflector embraces that portion of the light projector above the lip of the primary reflector and is indicated as section 5. This is formed by selectively treating the various portions 60 thereof, which have been heretofore determined as the critical points, so that the rays will be directed from the secondary reflector to assumed points in the roadway. In view 65 of the fact that the direction of all the rays from the primary reflector are calculated and

are known it is obvious that by correctly forming the surfaces of the secondary reflector, the rays may be directed to any desired position.

Illustrated in Figure 5 is the diagrammatic relation of the convergent or minus curve primary reflector with the compound base and the secondary reflector of the form shown in Figure 4. As has been explained the rays emanating from the source F will be in the form of a cone, inasmuch as the source has a finite size. This is particularly illustrated in Figure 1. It is to be noted however that only certain portions of the cone require particular consideration, as for example, in Figure 1, the side of the ray 10—R is the more critical because when redirected by a secondary reflector, it will be that portion of the ray cone which would tend to go above a horizontal line and therefore cause glare in an oncoming driver's eye. It is therefore the more critical side of the ray, which must be taken care of primarily in designing and plotting the secondary reflector. Similarly, on the other side of the reflector as shown in Figure 5, the opposite side of the cone of rays would be the more critical. In each case it is the forward side of the cone of rays.

The detail manner of constructing the primary reflector after assuming the values of a filament of the usual size and a distance between the focus and the intersection of the parametric plane with the principal curve at the point Po, which for purpose of example is here indicated as two inches, is to determine the angle of each cone of rays for each point plotted. The angle of the cone of rays is that angle between the innermost and outermost edges of the cone of rays resulting from the finite dimensions of the filament reflected from the point on the reflector. The typical example of this is shown in Figure 1, where the cone angle is the angle F—10—F'. Knowing the distance of the point on the reflector from the reference point, which on the primary point Po is two inches and knowing the size of the light filament and its tolerance, which is a definite amount, depending upon the light, the cone angle of cone of rays at that point can be readily determined. From this it can be determined what its subsequent direction is by determining the tangent angle of the reflector at that point.

For the next points, the distance to a point on a comparative paraboloid having a focal length of one inch, the distance of which points are known, was used. $\frac{1}{8}$ " vertical increments were set off from the parametric plane up toward the lip of the reflector to determine the comparative point on the generated curve. The tangent angle, will then be determined for each of the points at $\frac{1}{8}$ " intervals, which for this particular illustration, embraces 24 points.

The third determination was to add to the tangent angle at the point in consideration, an accumulative factor, which was $\frac{1}{2}$ the cumulative percentage increment of the cones of rays, only $\frac{1}{2}$ of the correction being added to the tangent to cause the required degree of change to be imparted to the critical rays of the cones of rays.

For example, the distance to P_0 from the reference point being two inches, the filament size being 2 mm., the first ray angle is approximately 134 minutes. At the next vertical increment the distance to the reference point changes slightly and the ray angle was determined to be 118 minutes. The first tangent angle is 45 degrees and this is plotted for the distance necessary to intersect the vertical line at the vertical increment in height which is $\frac{1}{8}$ inch. This determines the second point. But here, the tangent angle was found to be 43 degrees 19 minutes and to this is added $\frac{1}{2}$ of 10 per cent of 134 minutes or 6.7 minutes making a corrected tangent angle of 43 degrees 25.7 minutes and this was plotted until the next vertical interval was intercepted. For the third point, the tangent angle was 41 degrees 48 minutes and the accumulative factor was ten per cent of the first ray or zero plus ten per cent of the second ray or 13.4 minutes plus ten per cent of the third point or 11.8 minutes. The total accumulative factor is thus 25.2 minutes and the corrected tangent angle is thus 41 degrees 48 minutes plus $\frac{1}{2}$ of the accumulated factor of 25.2 minutes or 42 degrees .06 minutes.

As the points progress the accumulative factor also increases and while the tangent angle decreases yet as compared with the corresponding tangent of a parabola it increases. When the curve plotted is the one shown in Figure 3, this is changed and as compared with the parabola, the tangent angle decreases with a cumulative decrement. It is obvious that the accuracy of the points depends entirely upon the required accuracy of the light and the above calculations and assumptions are only given for purposes of example, and only generally correspond with the highly exact computations made, but which would not additionally clarify this example.

The generation of this curve might also be described in terms of increments added to or deducted from the angles which the tangents at the successive points in the curve make with the principal axis.

Starting with a tangent at 45° to the axis at a point in the parametric plane, the location of the successive points and tangents thereto may be determined by triangulation, using angles which the factors make with the principal axis as the reference, deducting $\frac{1}{2}$ of the difference between a right angle and the angle which the outer ray of a cone of rays, having the light source as its base and the ref-

erence point sought as the apex makes with the axis and by adding or deducting $\frac{1}{2}$ of the assumed percentage of the angle found between the sides of the cone of rays at such point and the cumulative increments of $\frac{1}{2}$ the assumed percentages of the cones of rays for the preceding successive points similarly determined in generating such curve.

For example to find the angle with $A-A$ to be given to the tangent at P_1 , starting with a tangent at P_0 at an angle of 45° to the axis $A-A$, point P_1 in the first plane of a uniformly spaced series of planes perpendicular to the axis through the points M_1 to M_{24} inclusive; produce tangent at P_0 to intersect the plane through M_1 at P_{1x} ; erect P_0A_1 parallel to the axis; P_0F , M_1F , and M_1A_1 are known; angle $A_1P_0P_{1x}$ equals tangent angle with the axis at P_0 ; A_1P_{1x} is found and M_1P_{1x} is then known; angle P_0FP_{1x} is found and angle $F_1P_{1x}F_2$ is found, which is the angle between the sides of the cones of rays at P_{1x} . Then the angle of the tangent with the axis at P_1 will be

$$45^\circ - \frac{P_0FP_{1x}}{2} \pm \frac{(F_1P_{1x}F_2xa) + b}{2} = \text{tangent at } P_1.$$

with $\frac{1}{2}$ the difference between the angles which the tangents at P_0 and P_1 make with the axis deducted from $A_1P_0P_{1x}$ will give P_1 and the converging tangents from P_0 and P_1 will intersect about halfway between the two points. With the intersection of the normals to P_0 and P_1 as the center of and radius of curvature the arc P_0P_1 is described for that section of the curve. In a similar manner the successive points are located and tangent angles with the axis determined and the curve P_0P_{24} is generated. The revolution of this curve about the axis will produce the surface of zone 1.

As shown in Figure 5, a number of critical or determinative points have been selected and the direction of the rays from these points illustrated. For example, the point PH is selected on the primary reflector 1 of the ray angle from the filament F reflected to the secondary reflector 5 is again reflected from the point SH from the light and at such an angle that this ray is substantially parallel to the horizontal axis and thus goes to the AH area.

Similarly with the other points PH' , SH' , AH' ; PA , SA , AA ; PC , SC , AC ; from the other portion of the secondary other points have been selected, PP , PM , PQ ; PS , PN , PL . From these points the rays from the focal point F are reflected to the secondary reflector at the points SP , SM , SQ ; SS , SN , SL ; from which the light is again reflected to the areas AP , AM , AQ , AS , AN , AN' , AN'' , AN''' , AL . A further point PB on the base 4 of the reflector is similarly selected and the critical light ray is again reflected from the point SB on the secondary reflector to the area AB .

The selection of these points while not material to this invention have been chosen by reference to certain arbitrary standards of Illuminating Engineering Societies which refer to the A point, B point, C point, etc., and which correspond with certain fixed distances in front of a vehicle having a light spaced a certain distance above the ground. These particular areas have been chosen and definite amounts of light have been estimated for these points as being the minimum amount necessary and for purpose of example these areas may be used in determining the curvature of the reflector surfaces.

In order to construct this portion of the reflector, the curve is revolved on the principal axis, thus making the proper shape. The limit to which the vertical increments are taken depends entirely upon the size of reflector unit desired. However, with the two inch minimum distance, the vertical height of this portion will be nearly three inches with final opening of approximately 7½ inches in diameter.

As has before been mentioned the secondary reflector is plotted in this instance by projecting the rays upward from the plotted points of the primary and with the knowledge of their actual angle with the principal axis.

In the modification of this reflector as shown in Figure 6, it will be noted that the secondary reflector is provided with a supplemental section 6a, which is illustrated in greater detail in Figures 10 and 11. The use of such a section aids the construction of the secondary reflector, so that the proper light is more effectively proportioned on the road in front of the vehicle. It will be noted however, that the section 7a of the reflector outside of the raised section 6a is of the common shape as shown in Figure 4, in order that the light may be properly distributed at the sides of the road. In this modification, it will also be noted that section 3 has been eliminated from the combined primary reflector and the paraboloidal section 4 immediately adjoins section 2, and such construction is entirely practicable altho the secondary reflector must be differently treated to properly position the rays.

A further modification is shown in Figure 7, in which the entire primary reflector is based on my generated curve as heretofore described. By properly plotting the secondary reflector, it is possible to use a complete increment or decrement curve for the primary reflector. The secondary reflector in both Figures 4 and 7, and particularly as shown in Figures 8 and 9 is modified to the extent of showing the corrugations or striations which aid in diffusing the light so that adjoining cones of rays will more effectively intermingle and give a complete graded light, the shape of the secondary reflector 5 in Figure 4 is shown in Figure 8 and if sections are

taken transverse on the lines a, b, c, d, e, and f, the resulting curvature will be as shown in Figure 9. Similarly the surface of the secondary reflector 5a shown in Figure 6 is illustrated in Figure 10 which also shows the projecting portion 6a. If in this figure, sections are taken on the lines g, h, i, j, k, l, and m, the resulting curvature will be as shown in Figure 11.

In Figure 12, I have shown a complete lamp, comprising in general the reflector shown in Figure 4. The principal parts are the upper primary reflector 1, the concentric portion 2, cylindrical sections 3 and a paraboloidal base not shown, the secondary reflector or section 5, the light source F and the shell 25. The secondary reflector is pivotally attached at 26 to facilitate adjustment by the screw 27, when the light is attached on the vehicle. The light unit F may also be adjusted to focus by means of the adjusting screw 28. In order to permit a strong illumination of objects relatively close, but at the sides of the vehicle, an opening 29 is provided in the side of the lamp which may be provided with suitable glass. The front is also protected by preferably clear glass 30. In view of the careful construction of the secondary reflector 5, it is substantially essential that a clear glass be used, as heretofore all of the rays have been treated and properly positioned to the respective locations on the ground in front of the vehicle and found desirable.

A duplex lamp shown in Figure 13 can be constructed from primary reflectors 7 and 8 abutting each other at the section thru the focus. These primary reflectors which are preferably of increment or decrement curve construction as shown in either Figures 1 or 3, may be extended any distance as desired and are adapted to be of such size that but one light projector would be used on the automobile and would have the principal axis of the light rays from the secondary reflector at such a distance apart as would be necessary. The direction of the rays is shown from the filament F by the dotted line, and the secondary reflector surfaces are indicated by the curves 7a and 8a respectively. These surfaces may be similar to the section 5 in that they are continuous curves without projections as shown in Figure 6 but in view of the adjoining primary reflector surfaces these curves must be suitably plotted in accordance with the method as outlined in connection with Figure 5.

In conclusion my invention consists principally in the direction and redirection of light rays from a definite filament which takes into account the errors in the position, size and shape thereof, together with the errors in the construction of the reflectors by the use of a generated reflector surface and which takes into account the critical position of the rays so that the more difficult controlled rays are

placed in such position in the final beam, that usual tolerance will not cause those particular cones of rays to seriously affect or alter the final light beam and the less sensitive reflector portions and the more easily controlled rays are placed in that part of the beam in which the greatest objection would be had, if the rays were seriously misplaced. It is to be understood that the surface generated is generated preferably by subtracting a proportionate part of the tangent angle at any assumed points of the reflector, which decrement is cumulative so that a greater concentration or diffusion may be had at will, and so that the critical portions of the rays are most effectively reflected from the primary reflector and so that the final correction can be made in the secondary reflector. It is to be further understood that the portion of the reflector below the parametric plane is preferably not substantially closer and the surfaces therefore are not more sensitive than the point on the primary reflector immediately at the parametric plane. By such construction, it is thereby possible to obtain a greater concentration or diffusion of the light, taking into account the errors in design tolerance and variations of the elements and if possible to give more complete and accurate control of all the light and to distribute it in front of the light projector in predetermined amount, so that uniform illumination without glare can be obtained.

While I have described several forms of the embodiments of this invention, it is to be understood that I do not desire to be limited to my particular forms of construction or theory of operation except as hereafter specifically claimed.

I claim:

1. In a headlight of the class described, in combination, a light source and a primary reflector adapted to reflect light therefrom, said primary reflector being a surface of revolution, the curve of which is irregular and is generated by adding to the tangent angle of a comparative parabola at points starting from the parametric plane and progressing outwardly, a progressive increment which is cumulative of all the preceding increments, such increments being $\frac{1}{2}$ the assumed percentage of the angles formed between the sides of the cones of rays for such points.
2. In a headlight of the class described, in combination a light source and a reflector adapted to reflect light therefrom, said reflector being a surface of revolution, the curve of which is irregular and is generated by deducting from the tangent angle of a comparative parabola at points starting from the parametric plane, and progressing outwardly, a progressive increment which is cumulative of all the preceding increments, such increments being $\frac{1}{2}$ the assumed percentages of the angles formed between the sides of the cones of rays for such points.

the angles formed between the sides of the cones of rays for such points.

3. In a headlight of the class described, in combination, a light source and a primary reflector adapted to reflect light therefrom, said primary reflector being a surface of revolution the curve of which is irregular and is generated by progressively varying in one direction the tangent angle of a comparative parabola at points starting from the parametric plane and progressing outwardly, each progressive variation being cumulative of all the preceding variations, such variations being $\frac{1}{2}$ the assumed percentage of the angles formed between the sides of the cones of rays for such points.

4. In a headlight of the class described, in combination, a light source and a primary reflector adapted to reflect light therefrom, said primary reflector being a surface of revolution, the curve of which is irregular and is generated by progressively varying in one direction the tangent angle of a comparative open conic section curve at points starting from the focal plane and progressing outwardly, each progressive variation being cumulative of all the preceding variations, such variations being $\frac{1}{2}$ the assumed percentage of the angles formed between the sides of the cones of rays for such points.

5. In a headlight of the class described, in combination, a light source and a reflector adapted to reflect light therefrom, said reflector being a surface of revolution the curve of which is irregular and is generated by deducting from the tangent angle of a comparative parabola at points starting from the parametric plane, and progressing outwardly, a progressive increment which is cumulative of all the preceding increments, such increments being $\frac{1}{2}$ the assumed percentages of the angles formed between the sides of the cones of rays for such points, a secondary reflector located above the primary reflector at a general angle of substantially forty-five degrees to the axis of the primary reflector, the surface of said secondary reflector starting at its inner end substantially in contact with the rim of the primary reflector, having a curve generated progressively outward, so that the angle which the tangent at each successive point makes with a plane through the axis of the primary reflector perpendicular to the forwardly horizontal axis of the headlamp will vary from forty-five degrees by an amount equal to $\frac{1}{2}$ of the angle which the forward ray of a cone of rays reflected by the primary reflector makes with said plane less $\frac{1}{2}$ of the angle to the horizontal axis of the headlamp assumed for the direction to be given to such ray when reflected by such point on the secondary reflector and to thereby assure that no ray of any cone of rays reflected by the primary reflector onto the sec-
